Primary Examiner — Paula Greene(74) *Attorney, Agent, or Firm* — Laurence A. Greenberg;
Werner H. Stemer; Ralph E. Locher(57) **CLAIM**

The ornamental design for a magnifier, as shown and described.

DESCRIPTION

FIG. 1 is a side view of the magnifier, showing our new design;

FIG. 2 is a top plan view thereof;

FIG. 3 is a top view thereof in a half open position; and,

FIG. 4 is a top view thereof in a fully open position.

The broken lines form no part of the claimed design.
